SPRAYING DEVICE FOR LIQUIDS

Hermann Maltner, Frankfurt am Main, Germany

Application June 4, 1951, Serial No. 229,674

Claims priority, application Germany June 3, 1950

2 Claims. (Cl. 299—88)

The invention relates to a spraying device for liquids, especially perfumes, which can be carried in a handbag or pocket, and which consists of two tubular containers, one of which is adapted to slide in the other, one of these containers holding a liquid tank with the nozzle head and a pump cylinder connected thereto, whereas the other container carries a pump plunger, which can slide into the cylinder against the action of a spring. In the known atomisers of this type, the stand pipe in which the liquid rises and the air nozzle terminate freely into a neck of the liquid tank, which is provided with a hole in its wall for the outlet of the atomised medium. The neck of such known types of atomisers is, furthermore, surrounded by a cap, which can be locked against the other sleeve container, and which, in the closed position of the device, covers the hole in the wall of the neck. This locking cap constitutes therefore the only closure against the escape of liquid. If tightly fitted on the neck of the liquid tank, this cap may prevent the leaving of the medium to be vapourised from the hole in the neck. Even the closed position however, some of the liquid to be atomised can still flow from the stand pipe into the neck, especially if the tank communicates freely with this neck. This possibility of the liquid to be atomised escaping into the neck causes, however, when the closing cap is loosened with a view of using the atomiser, an excessive outgoing of this liquid.

The present invention comprises a new construction of these pocket atomisers, which ensures a tight seal of the stand pipe in the closed position of the sprayer or atomiser, and which prevents a flow of liquid into the neck of the atomiser when the atomiser is not in use. In a container of the described design, where the spray nozzle for the liquid to be atomised terminates in a neck portion of the liquid tank, and which contains an air nozzle, co-ordinated to the end portion of the liquid nozzle, and where a cap, which locks the two sleeve container parts against each other in the closed position, surrounds the neck; in such a container the cap is coupled with a sealing organ, which shuts off the nozzle in the locked position. The two nozzles are suitably arranged in a plug or nozzle head which seals the neck against the liquid container, and these nozzles are preferably designed as passages drilled into and traversing the said plug, whereby the sealing organ is constructed as a sealing plate or disc, co-ordinated to the upper face of the plug.

The cap is, preferably, guided to slide axially, and against the pressure of a spring, along the neck by means of a pin and bayonet slot connection. This cap is, furthermore, rotatably held in the inserted position and carries the sealing disc by means of an internal pin.

The air jet orifice terminates, preferably, inside an annular depression of the plug, which depression surrounds the atomising or spray nozzle. The plug is, furthermore, provided with an air vent passage for the liquid container, which is, preferably, controlled by a spring-loaded throttle valve.

The new arrangement leads, apart from a simple design of the nozzle head, to an absolutely safe seal of the atomiser nozzles and of the air vent passage in the closed position of the atomiser, and prevents then the liquid medium from leaving the tank and from flowing into the neck sleeve of the container.

Referring to the drawings:

Figures 1 and 2 are two longitudinal sections, showing the subject of the present invention in the position of

2

use, the respective sections being at an angle of 90 degrees to one another.

Figure 3 shows the subject of the invention, in its closed condition, in a side view.

Figures 4 and 5 show sections through a second design of the closure, in two sectional views, the respective section being at an angle of 90 degrees to one another, and

Figure 6 is a cross section, taken on the plane VI—VI, Figure 5.

Arranged to slide in a tubular casing 1 is another tubular casing 2, the outward movement being limited by the holding screws 4 on the container 1, which engage into slots 3 of the container 2.

15 A spring-clip 6, fixed on the cover plate 5 of the tubular casing 2, holds a nozzle head or plug 7 of a liquid tank 8, this tank having a filler screw plug arranged at its bottom. To each side of the tank 8, and inside the tubular casing 2, is arranged a pump cylinder 10, the two pump cylinders being connected to a transverse duct 12 in the nozzle head 7 by way of pipes 11. In the cylinders 10, plungers 13 are arranged, the rods 14 of these plungers abutting against the bottom plate of the container 1. Helical compression springs 15 are mounted on the plunger rods 14, one end of each of these springs pressing against the base end flange 16 of the corresponding plunger rod, while the other end of each spring 15 bears against the respective plunger wall 17, the springs thus endeavouring to hold the container 2 in its extended position.

The nozzle head 7 has two passages 18, 19, the passage 19 terminating in a nozzle or jet orifice 21, which is surrounded by a circular groove 20. The passage 19 also registers with a small tube 22, passing down the tank 8. A duct 23 terminating in a jet orifice which opens into the circular groove 20, passes from the transverse passage 12 of the plug or nozzle head 7. This nozzle head or plug 7 is provided with a tubular extension 24, which has an outlet opening 25 therein, arranged in alignment with the nozzle duct 23.

By means of a pumping motion effected by a relative displacement of the two tubular casings 1 and 2, pressurised air, coming from the pump cylinders 10, is driven out, by way of the tubular ducts 11, the transverse passage 12, and the nozzle duct 23. This air entrains and atomises the liquid sucked from the tank 8 by way of the nozzle 21, and drives the atomised liquid out of the outlet hole 25. The passage 18 in the nozzle head 7 serves for the intake of air into the tank 8, and facilitates the suction of liquid through the tube 22.

50 In order to avoid the escape or evaporation of liquid from the atomiser 7, when the device is not used, and to obtain a tight seal, the tubular extension 24 carries a cap 27, which can be axially displaced by pins 28 engaging bayonet-slots 26 and locked in the closed position. This cap is secured against removal by means of fixed screws 28, the ends of which engage in the slots 26. A helical spring 29 is arranged in the cap 27 in order to press against the tubular extension 24, and urge the cap 27 into its open position, in which the outlet part 25 of the tubular extension 24 is exposed.

The cap 27 has a flange rim 30, which has two diametrically opposed notches, and in the retracted position of the container 2, this rim is engaged by two clip-like projections 31 of the container 1 by engaging the said notches on the projections 31 and turning the cap, thereby locking the atomiser in its closed position, as shown in Figure 3. The cap 27 carries, on an axial pin 32, a cup 33, which, by means of a rim thereon holds a sealing washer 34, made from deformable material, e. g. rubber. This washer bears in the closed position of the cap 27 against the face of the nozzle head or plug 7, thereby closing the groove 20 and the nozzles 21, 23 and the air inlet passage 18. Thus no liquid can leave the tank 8 when the cap 27 is in its closed position.

75 In the modification shown in Figures 4 to 6, the plug 7 is mounted inside a tubular sleeve 35, which carries a screw cap 36. This cap 36 carries, on a rotatable axial stud 37, the valve 33 with a sealing disc 34. If the cap 36 is screwed down, this disc 34 descends and eventually bears against the face of the plug 7. A spring loaded

80

throttle valve 38 is arranged in the air inlet passage 18. This valve 38 admits the entry of air into the tank 8 only in accordance with the vacuum establishing itself in this tank.

The closure disc 33 carries a needle valve 39, which ensures the positive closure of the evacuation passage 18 of the plug 7, when the atomiser is closed, in which case the needle 39 closes the passage 18.

The bottom of the tubular casing 1 has a hole 40, which enables the tank to be refilled, after unscrewing the screw plug 9, when the atomiser is in its closed position.

Having thus described the invention, what is claimed as new and described to be secured by Letters Patent is:

1. In a device for spraying liquid from a tank by air pressure discharged from pressure generating cylinders mounted in one part of a telescoping casing, a dispensing head on the part of said casing carrying the cylinders, said head being in the form of a plug having a flat face provided with a discharge orifice, an air vent duct for the tank in the plug, a liquid discharge tube, air pressure duct means in the head communicating with said cylinders and having an air jet nozzle portion disposed at an angle to the liquid discharge tube, a tubular extension on the plug having a lateral port to one side of said flat face and in alignment with said air jet nozzle, said extension having bayonet slots, a cap mounted on said extension for partial turning and having means entering said slots to slidably guide the cap on the extension, a spring confined between the inner end of the cap and the upper end of the extension, an axial pin on the cap, means on the inner end of the pin to seal the plug, a rim on the lower end of the cap and having diametrically disposed notches, projections on the part of

10

the casing into which the part carrying the head and cylinders telescopes for entering said notches, whereby, upon

15 the cap being slidably moved to sealing position and turned as permitted by the bayonet slots the rim will

20 engage beneath the projections to hold the parts of the casing in collapsed condition.

2. In a device for spraying liquid from a tank by air pressure discharged from pressure generating cylinders mounted in one part of a telescoping casing, a dispensing head on the part of said casing carrying the cylinders, said head being in the form of a plug having a flat face provided with a discharge orifice, an air vent duct for the tank in the plug, a liquid discharge tube, air pressure duct means in the head communicating with said cylinders and having an air jet nozzle portion disposed at an angle to the liquid discharge tube, a tubular extension on the plug with a lateral port in line with the said air jet nozzle, a cap screw-threaded on the tubular extension, and sealing means carried by a pin whose upper end is swivelled to the cap, and a needle valve on the cap for entering the said air vent duct when the cap is screwed down to bring the sealing means in engagement with the sealing face of the plug.
